UNITED STATES PATENT OFFICE.

JOHN F. O'CONNOR, OF CHICAGO, ILLINOIS, ASSIGNOR TO WILLIAM H. MINER, OF CHAZY, NEW YORK.

SPRING DRAFT-RIGGING.

1,253,088.

Specification of Letters Patent.

Patented Jan. 8, 1918.

Application filed August 25, 1916. Serial No. 116,772.

To all whom it may concern:

Be it known that I, JOHN F. O'CONNOR, a citizen of the United States, residing at Chicago, in the county of Cook and State of Illinois, have invented a certain new and useful Improvement in Spring Draft-Rigging, of which the following is a full, clear, concise, and exact description, reference being had to the accompanying drawings, 10 forming a part of this specification.

This invention relates to improvements in spring draft rigging.

One object of this invention is to provide a spring draft gear which may be cheaply 15 manufactured and easily applied and wherein the pulling and buffing shocks are transmitted to the sills of the car by means of a single fixed key.

In the drawing forming a part of this 20 specification, Figure 1 is a vertical longitudinal section of a portion of a draft rigging showing my improvements in connection therewith. Fig. 2 is a horizontal sectional view taken substantially on the line 2—2 25 of Fig. 1 and showing the parts of the draft rigging in normal position. Fig. 3 is a transverse, vertical sectional view taken substantially on the line 3—3 of Fig. 1. And Fig. 4 is a broken detail view of the forward portion of one of the yoke arms.

In said drawings, 10—10 denote channel shaped center or draft sills of a car between which the parts of the gear are mounted. The gear proper preferably comprises a 35 front follower 11, rear follower 12, vertical twin arranged springs 13—13 separated by a spacer block 14, the gear being operated under draft by means of a horizontal yoke A. The gear proper is held in position by 40 means of a tie plate 15 which is detachably connected to the lower flanges of the sills by means of clips 16 and bolts 17.

The front follower 11 is prevented from forward movement by means of a fixed, horizontally extending wide key 18 mounted in correspondingly shaped slots in the sills 10—10, the front follower 11 normally engaging the rear edge of said key 18. As also appears from Fig. 2, the key 18 passes 45 through suitable slots provided in the side arms of the yoke A. Each of the side arms of the yoke A is slotted at its forward end in the manner most clearly indicated in Fig. 4. Each slot comprises a rectangular portion 19 with a rearwardly extended, cen-

trally located narrower portion 20, the latter being to accommodate the forward movement of the yoke A on the fixed key 18, as will appear from an inspection of Fig. 2. The draw bar 21 has the butt thereof transversely slotted, the slot comprising a wide section 22 near the center, a forwardly extended narrower section 23 which permits the rearward movement of the draw bar relatively to the fixed key 18, and a rearwardly extended narrower section 24 to accommodate the key 18 and permit forward movement of the draw bar. The wider portion of the slot in the draw bar is provided to accommodate two narrower keys 25 and 26 arranged respectively above and below the fixed key 18. Said keys 25 and 26 pass through the enlarged portions 19 of the slots in the arms of the horizontal yoke and normally engage against the forward edges of 75 said slots. The yoke arms are preferably provided with laterally extended reinforcing flanges 27 at the forward ends of the slots therein and against which the keys engage. As clearly indicated in Fig. 2, the upper 80 and lower portions of the slotted butt end of the draw bar are connected by a rectangular brace 28 which is accommodated in an elongated slot 29 in the key 18. The sides of the draw bar are provided with 85 reinforcing flanges 30 surrounding the slot in the draw bar, the shape and contour of said reinforcing flanges being clearly illustrated in Fig. 1.

As shown in Fig. 3, the keys 25 and 26 are 90 of similar construction and each has a flanged end 31, the keys, when inserted being oppositely arranged as shown in Fig. 3, whereby the flanges 31 overlap the ends of the fixed key 18. The keys 25 and 26 are 95 maintained in position by any suitable means such as the cotters 32—32.

In operation, upon buffing movement, the yoke A is prevented from rearward movement since it engages the fixed key 18. Consequently, the rear follower 12 is prevented from rearward movement by the yoke A and as the draw bar moves inwardly over the fixed key 18, the rear face of the draw bar butt will engage and operate the front follower 11, thus compressing the springs. The amount of compression is or may be limited by the spacer 14, the length of which can be varied as desired. In draft, the front follower 11 is held stationary by the fixed key 110

18 and the yoke A is pulled forwardly by the two keys 25 and 26, which are engaged and operated by the draw bar, said keys 25 and 26 and the yoke A sliding over the fixed 5 key 18. By this movement, it is apparent that the rear follower 12 will be operated and the springs compressed against the front follower.

The arrangement which I have provided 10 is simple, eliminates stop castings, may be readily assembled and disassembled and may be employed in standard sill spacing. Furthermore, the gear proper may be inserted and removed from below without disconnecting or disturbing the draw bar and yoke.

I claim:

1. In a draft rigging, the combination 20 with a draw bar, a yoke, and shock absorbing mechanism within the yoke, of two movable keys, and a fixed key, all of said keys extending transversely through the draw bar and the yoke, the fixed key acting as a front stop for said mechanism and preventing rearward movement of the yoke, the 25 movable keys connecting the draw bar and yoke under draft.

2. In a draft rigging, the combination 30 with a shock absorbing mechanism including a front follower and a rear follower and a horizontal yoke, of a fixed key arranged to prevent forward movement of the front follower, said key being extended through slots in the arms of said yoke and arranged to prevent rearward movement of the latter, 35 but permitting forward movement thereof, and means for operatively connecting said yoke with the draw bar under draft, said means including a pair of keys located one directly above and the other directly below 40 said fixed key.

3. In a draft rigging, the combination 45 with a draw bar and a horizontally arranged yoke, of means for operatively connecting the draw bar and yoke under draft, shock absorbing mechanism insertible from below and between the arms of said yoke, and

means for preventing rearward movement of the yoke whereby the latter acts as a rear stop for the shock absorbing mechanism, said means including a fixed key passing 50 through a slot in the draw bar.

4. In a draft rigging, the combination 55 with a draw bar, and shock absorbing mechanism including a front follower against which the butt of the draw bar normally bears, a fixed key extending through the draw bar and also normally engaging said front follower and preventing forward movement of the latter, and means connected with the draw bar for actuating the shock 60 absorbing mechanism under draft, said means acting as a rear stop through the intermediary of said fixed key under buff.

5. In a draft rigging, the combination 65 with draft sills, a fixed key extending horizontally between said sills, a horizontal yoke slideable forwardly with respect to said key, but prevented from rearward movement thereby, shock absorbing mechanism insertible from below between the arms of said 70 yoke, said key acting as a front stop for the shock absorbing mechanism under draft, a draw bar, and means operatively connecting the draw bar and yoke under draft, said means comprising a pair of keys slideable 75 with respect to the fixed key.

6. In a draft rigging, the combination 80 with a draw bar, a yoke, and shock absorbing mechanism, of three transversely extending keys all located forwardly of the shock absorbing mechanism, certain of said keys being fixed and adapted to prevent rearward movement of the yoke and act as a front stop for said mechanism, the remainder of said keys being movable and adapted to operatively connect the yoke and draw bar 85 under draft.

In witness that I claim the foregoing I have hereunto subscribed my name this 22nd day of August, 1916.

JOHN F. O'CONNOR.
